UNITED STATES PATENT OFFICE.

FREDERICK GEORGES AND PIUS P. GEORGES, OF NEW BRITAIN, CONNECTICUT.

AUTOMATIC GATE TENDER.

Application filed February 27, 1923. Serial No. 621,642.

To all whom it may concern:

Be it known that we, FREDERICK GEORGES and PIUS P. GEORGES, citizens of the United States, residing at New Britain, in the county of Hartford and State of Connecticut, have invented certain new and useful Improvements in Automatic Gate Tenders, of which the following is a specification.

Our invention relates to improvements in automatic gate tenders for use in controlling the protecting gates at highway railroad crossings, and the object of our improvement is to provide means having electrical actuating devices whereby the control of the gates will reside in circuit closing devices that are operated by the train, having means for lowering and raising the gates, and which means are simple, reliable, and efficient.

In the accompanying drawing:—

Figure 1 is a side elevation of our improved automatic gate tender.

Figure 2 is a plan view of a section of track at a highway crossing and a set of gates and showing the contact rails for closing the electrical circuits.

Figure 3 is a side elevation on an enlarged scale of one of the gates, being in part broken away to show the checking pawl.

Figure 4 is a similar side elevation showing a modified form of the means for operating the gate.

Figure 5 is a side elevation of certain parts that are shown in Fig. 1 and on the same scale in a different position from that shown in the figure mentioned.

Figure 6 is a diagram of connections.

Our improved automatic gate tender comprises electrically operated means for lowering and raising a set of gates 10 that are actuated by means of circuit closing devices that are operated by the train.

The train carries some suitable cross-connecting device for inter-connecting certain contact rails 11 that are arranged in pairs, the different pairs being positioned at suitable locations relatively to the tracks 12. There is one pair of contact rails 11 on each side of the crossing 13, one pair being at the side of approach of the train to the crossing and the other at the side of departure from or leaving the same, the former serving to make the proper connection for lowering the gates 10 and the latter serving to make connection for raising the gates.

With a double track road, as shown, and assuming that the trains pass along the right hand track, the contact rails 11 on the upper right side of Fig. 2 serve as the means for closing the circuit for lowering the gates 10 and the contact rails 11 at the lower and left hand side do the same, these particular rails being cross-connected. The contact rails 11 in the upper left hand side and lower right hand side are similarly cross-connected and serve to make the proper circuits complete for raising the gates.

The contact rails 11 are positioned in parallelism, separated by a moderate space, and are positioned as a set between the track rails 12 and located at a proper distance from the crossing 13 to permit of effecting the operation of the gates in a proper manner to afford the desired protection for the crossing 13.

Also, one or more signal lamps 15 may be displayed at the proper time and extinguished when not needed.

For lighting the lamps 15 a single-pole switch 16 is shown.

For operating the gates a pair of double-pole knife-switches 17 are shown, there being one for each movement of the same.

Electric current may be supplied through the medium of a pair of main supply wires 18.

Thus the branch circuit 19 is provided for the lamp 15 and its control switch 16.

The power is provided by means of an electric motor 20 and this may be of the single-phase alternating-current form, requiring two wires. The branch circuit 21 contains the motor 20 and the two sides thereof are connected respectively to the two hinge-contacts 22 of the two knife-switches 17. Thus when the knife-switches 17 are open the motor 20 will be inoperative and when either of these two switches is closed the motor may or may not be operative, depending upon the particular conditions that exist electrically beyond the make-and-break contacts 23 that cooperate with the knife-switch blades 24.

Each pair of make-and-break contacts 23 is connected to a pair of contact rails 11, the connections, as shown, being made by the individual wires 25 that are connected to the cross-connecting wires 26 that make the diagonal inter-connections of the contact rails 11.

Thus, when one of the knife-switches 17 is closed the motor 20 will be operated responsive to the closing of the circuit at the proper corresponding contact rails 11.

5 Normally the knife-switch 17 corresponding to the contact rails 11 on the approaching side of the crossing 13 is closed so that the motor will be operated responsive to the approach of the train and the other knife-switch 17 is open. After the train has passed from the approach side or near side to the far side of the crossing 13 the electrical circuit is closed so as to restore the normal conditions just described. In the meantime, 10 simultaneously with the lowering of the gates 10, the first, or gate-lowering knife-switch 17 has been opened and the other, the second, or gate-raising knife-switch 17 has been closed, the parts being thus set for 15 restoring to the normal condition by cross-connecting the contact rails on the far side of the crossing.

The mechanism for operatively connecting the motor 20 and the gates 10 may be of any 20 suitable form, the said mechanism comprising also the needed elements for operating the switches.

Thus the gate 10 is represented as being supported by means of a shaft 27. The main 25 shaft 28 is driven from the motor 20 through the medium of suitable inter-connecting devices such as the belt 29 and a set of gears 30 housed in the gear case 31.

The gate-shaft 27 may be provided with 30 a crank-arm 32 that is connected by means of a link 33 with a driving-crank-arm 34 on the main shaft 28. A modified arrangement comprises the use of a gear-wheel 32^a on the gate-shaft 27 that cooperates with the 35 toothed-sector 33^a that is operatively connected to the driving shaft 28.

The arm 34 may also close the lamp-switch 16 through the medium of a link 35.

The knife-switches 17 are operated by 40 crank-arms 36 on the main shaft 28 and suitable intermediate connecting devices. Thus a lower link 37 connects with the crank-arm 36 and an upper link 38 connects with the handle 39 of the knife-switch 17, and intermediate said links is a swinging member 40 that is pivotally supported by means of a post 41.

In order to check the gate 10 from accidental lowering we provide on the gate-shaft 27 a ratchet-wheel 42 and a checking-pawl 43 for cooperating therewith.

The pawl 43 is provided at the upper end of a generally upwardly directed arm or branch 44 of a bell-crank 45 that is supported on a pivot 46 and has a laterally directed branch 47. The latter has on the free end a contacting nose 48 that rides on the periphery of a control-cam wheel 49 and which is provided at a suitable position with 65 a depression or notch 50. The cam wheel

49 is operatively connected with the main shaft 28 through the medium of a crank-arm 51 that is connected with said cam wheel 49 and a link 52, the latter being connected to one of the crank-arms 36 or with 70 a separate crank-arm as may be convenient.

When the nose 48 is in the notch 50 the pawl is in the checking position. A slight rotation of the cam wheel 49 serves to lift it out of the notch and free the gate from 75 the checking control.

As described, the motor is adapted for rotation in one direction only and is alternatively used for lowering and raising the gates and the electrical connections and so switches are inter-related so as to effect the one result or the other, and the rotative movement of the motor and main shaft are changed to proper reciprocating movements 85 for the gates and for the switches.

The main shaft 28 is always rotated in the same direction and carries a set of crank-arms consisting of one for operating the gate and a pair connected individually with the electric switches, the crank-arms being 90 mechanically connected with the particular mechanism to be operated in each case.

The operation is as follows:—

In the position shown in Fig. 1 the gate is closed, the front switch 17 is closed, and 95 the rear switch 17 open. In the position shown in Fig. 5 the gate is open, the front switch 17 is open, and the rear switch 17 is closed. The change from the position of Fig. 1 to that of Fig. 5 or the reverse 100 represents substantially a rotation of the main shaft to the extent of one-hundred and eighty degrees.

The electric circuits are arranged to connect the motor with the current supply 105 mains through the medium of one of the switches and one set of contact rails in one case and the other case through the other switch and set of contact rails. One set of contact rails, as shown in Fig. 6, comprises the upper right-handed pair and the lower left-handed pair, and the diagonally arranged cross-connections, and the other set comprises the upper pair at the left and the lower pair at the right, similarly 110 cross-connected.

The set that includes the upper right pair of contact rails corresponds to the approach side of the crossing that is protected by the gate under conditions of right-handed travel along the double-tracked way 115 and the upper left pair corresponds to the departure side.

The electric circuits are arranged to include the front switch, as shown in Fig. 120 6, with the contact rails on the departure side of the crossing and to include the rear switch with those on the approach side.

Thus the front switch is active when the departure contact rails are cross-connected, 125

as by suitable short-circuiting devices on the locomotive, and the rear switch is active when the approach contact rails are connected together.

5 The mechanical connections serve to open the active switch in each case after the corresponding and proper movement of the gate and essentially simultaneously the inactive switch is closed or set so as to become the active switch for the next movement of the gate.

Said mechanical connections and the operation thereof comprise the following:—

10 The main shaft 28 comprises as a part of its structure a set of crank-arms, as mentioned, respectively the arm 34 and the two similar arms 36.

15 The arm 34 is the driving crank-arm for the gate 10 and serves to operate the same through the medium of the link 33 and the crank-arm 32 that is incorporated in the structure of the shaft 27 that carries the gate 10. Rotation of the main shaft 28 by the motor 20 through the medium 20 of the sprocket chain or belt 29 serves to provide a longitudinally reciprocating movement to the link 33. Thus the crank-arm 32 for the gate 10 is moved back and forth through a limited angular movement, 25 and the parts are constructed and arranged so that this movement is correct and proper for effecting the desired range of movement for the gate 10. When the arm 34 is directed downwardly corresponding to its 30 lowest position the gate 10 is at the horizontal or closed position and when said arm 34 is at the uppermost position the gate is in the fully elevated or open position.

35 The crank-arms 36 are operatively connected to the knife-switches 17 through the medium of the intermediate connecting devices already mentioned and comprising the swinging member 40, the link 37 intermediate the same and the crank-arm 36, and the link 38 intermediate said swinging member 40 and the handle 39 of the knife-switch 17.

40 Considering Fig. 1, which is a diagrammatic view, the gate 10 is down, one switch 17 is closed and the other switch 17 is open. The parts are constructed and arranged so that as the car enters upon the circuit closing position, corresponding to the approach 45 to the crossing, the proper switch 17 is closed. Then, upon the closing of the circuit the motor is started and the gate is lowered to the position shown in Fig. 1 and just as the lowermost position is reached 50 the proper switch 17 is opened and the motor stops. At some time previous to the stopping of the motor as described the mating switch 17 is closed. The approach side 55 of the crossing is represented in Fig. 2 by the contact rails 11. The contact rails 12

in said figure represent the departure side. As the car passes between rails 11 and 12 there is no action. As the car reaches rails 12 the operations described are essentially repeated, the difference being that the result is the elevation of the gate in lieu of the lowering thereof.

70 The structure of Fig. 4 differs from that which has been described in the use of a segment in lieu of a crank-arm for operating the gate.

75 We claim as our invention:—

1. In combination in an automatic gate tender, a gate supported by a gate shaft, an electric motor, a main shaft rotated by 80 said motor, a crank on said main shaft operatively connected to said gate shaft, a track extending past said gate, said track having a pair of contact rails on each side of said gate, a motor control switch for each pair of contact rails, a current supply line connected to the motor and to one side of said switches, the other side of each of said switches being connected individually with a pair of contact rails, and means 85 operated from said main shaft for alternately opening one of said switches and closing the other thereof responsive to rotation of said main shaft.

2. In an electrically-operated and train-controlled gate tender, a gate for being alternately lowered and raised by a swinging movement, a motor, a main shaft rotatively operated by said motor, a crank-arm on said main shaft operatively connected to said 90 gate, a control switch for each movement of said gate, means for operating said switches from said main shaft, and contact rails, arranged in pairs, for individually closing the circuits for said switches, one 95 pair of rails being on one side of the gate and another pair of rails being on the other side of the gate.

3. In an automatic gate tender, a gate supported for being changed alternately to the obstructing and to the non-obstructing position, a pair of electric control switches, an electric motor, a main shaft operatively connected to said motor, track rails provided with circuit-closing rails, electric circuits 110 selectively connecting said motor with said circuit-closing rails and switches, a pair of crank-arms connected individually with said switches, and a third crank-arm connected with said gate, said crank-arms being incorporated in the structure of said main shaft.

4. In an automatic gate tender, a gate supported for being lowered and raised, two pairs of contact rails located at opposite 115 sides of said gate, a pair of electric switches having each an operating lever, a one-way electric motor and a main shaft driven thereby, a source of supply for electric current, 120 a pair of electric circuits arranged to con- 125

nect said motor to said supply, one through the medium of one switch and one pair of contact rails and the other through the medium of the other switch and pair of contact rails, individual connecting means intermediate said shaft and the gate and the two switches, and said connecting means being

constructed and arranged to operate in synchronism so as to effect alternatively the opening of one switch and the closing of the other simultaneously with a movement of the gate in one direction or the other.

FREDERICK GEORGES.
PIUS P. GEORGES.
